TOY DOG FIGURE

Harry Meth and Susan Lake, Cincinnati, Ohio, assignors to General Mills Fun Group, Inc., Minneapolis, Minn.

Filed Oct. 26, 1970, Ser. No. 25,669

Term of patent 14 years

Int. Cl. D21—01

U.S. Cl. D34—2

FIG. 1 is a perspective view of a toy dog figure illustrating our new design;

FIG. 2 is a front view thereof;

FIG. 3 is a side elevational view thereof;

FIG. 4 is a back view thereof;

FIG. 5 is a top plan view thereof; and

FIG. 6 is a bottom plan view thereof.

We claim:

The ornamental design for a toy dog figure, substantially as shown.
